MOLD

John B. Dickman 3rd, Washington, D. C., assignor of one-half to Philip L. Gertz, Brooklyn, N. Y.

Application January 22, 1953, Serial No. 23,255

Term of patent 7 years

(Cl. D44—1)

FIG. 1.

FIG. 2.

FIG. 3.

I claim:

The ornamental design for a mold, substantially as shown.
